C. E. RENO.
AUTOMOBILE RADIATOR.
APPLICATION FILED OCT. 7, 1920.

1,431,043.

Patented Oct. 3, 1922.

Inventor:
Charles E. Reno,

his Attorneys.

UNITED STATES PATENT OFFICE.

CHARLES E. RENO, OF WEBSTER GROVES, MISSOURI.

AUTOMOBILE RADIATOR.

Application filed October 7, 1920. Serial No. 415,423.

To all whom it may concern:

Be it known that I, CHARLES E. RENO, a citizen of the United States, residing at Webster Groves, St. Louis County, Missouri, have invented new and useful Improvements in Automobile Radiators, of which the following is a specification.

This invention relates to automobile radiators.

10 The primary object of the invention is to provide an improved means for heating the water in the radiator to prevent freezing.

Another object of the invention is to provide means for stirring or agitating the water when the engine is running.

In the drawings, in which I have shown the invention,

Fig. 1 is a plan view.

Fig. 2 is a vertical cross sectional view on the line 2—2 of Fig. 1.

Fig. 3 is a sectional view on the line 3—3 of Fig. 2 showing a form of valve for controlling the heat.

As shown, the radiator 1 is arranged to contain water. In the lower part of the radiator I provide a heating chamber 2 and in the opposite part of the radiator a heating chamber 3. Heat is delivered into the lower heating chamber 2 from a burner 4 which is conventionally shown in Fig. 1.

I may employ any appropriate form of burner and do not restrict myself to any particular type. Heat from the burner 4 is conducted into the chamber 2 through a passage 5 and from the chamber 2 heat is conducted into the chamber 3 through a passage 6. The chamber 2 is provided with a regulating device to prevent over-heating of the water and to discharge the heated air

40 when the temperature reaches a predetermined degree of heat. As shown, the passage 7 extends from the chamber 2 and encloses a valve 8 which is normally held upon its seat in closed position by a spring 9.

45 When the pressure within the chamber 2, due to the increase of heat therein, reaches the desired degree the valve 8 is forced open by the pressure of the heated air permitting the hot air to pass out. By use of this device freezing of the water in the radiator may be prevented and the water may be heated before starting the car, when desired.

50 My invention also comprises means for agitating the water to maintain proper circulation when the car is running.

As shown, the radiator comprises a number of vertical tubes 10 open at their upper and lower ends and permitting free passage of the water therethrough. The tubes 10 are lined with either isinglass or mica 11. 60 It is known that water does not closely adhere to either isinglass or mica and does not readily freeze in connection therewith. I provide also a pair of crank shafts, one of which is arranged horizontally above the 65 ends of the tubes 10 and one of which is supported horizontally below the tubes 10. The upper crank shaft 12 is journaled in bearings in supports 13. The supports 13 are in the form of partitions forming chambers 70 into which the ends of the upper shaft 12 extend. The outer walls of the chambers have openings provided with sliding closures 14 which may be moved to open position to afford access to the bearings of the 75 crank shaft. The lower crank shaft 15 is supported in bearings in supports 16 in the form of partitions forming chambers which are closed from the water in the radiator and into which the ends of the crank shaft 80 15 extend. The outer walls of the lower chambers have openings provided with sliding closures 17 which may be moved to open position to afford access to the bearings of the shaft 15. 85

The cranks of the shafts 12 and 15 are connected by agitator rods 18 which extend through the tubes 10. When the shafts 12 and 15 are in rotation the rods 18 are oscillated vertically, thereby agitating the water 90 in the tubes 10 and causing the water to circulate so that the water is more quickly heated and prevented from freezing.

The end of one of the crank shafts, which in the present case is the crank shaft 12, is 95 provided with a beveled gear 19 meshing with a gear 20 on the end of a drive shaft 21. The drive shaft 21 has a pulley 22 thereon and a belt 23 passes around the pulley 22 and is driven by a pulley 24 on the 100 fan shaft 25 of the engine.

It is known that the fan shaft 25 is driven by the engine so that when the engine is running the shaft 21 will be rotated, thereby operating the crank shafts 12 and 15 and 105 the rods 18. This facilitates the circulation and heating of the water and also prevents freezing.

From the foregoing it will be seen that my invention completely serves its purposes. 110

It is free from complications, it is of economical construction and may be easily embodied within an automobile.

I do not restrict myself to unessential features, but what I claim and desire to secure by Letters Patent, is:—

1. In a radiator, a water chamber, a number of heat chambers within and spaced from the walls of the water chamber permitting the water to contact with different walls thereof, a passage through one side of the water chamber for conducting heated air through one of the heat chambers, a passage from the heat chamber into which the heated air is conducted for conducting heated air into the other heat chamber, and a device in connection with one of said heat chambers arranged to yield to the pressure of the heated air to permit heated air to pass from said chamber.
2. In a radiator, a water chamber, a number of heat chambers within the water chamber, means for delivering heated air into one of the heat chambers, a passage for conducting heated air from the first-named heat chamber to the other one, a passage for conducting the heated air out of said heat chambers, and means for controlling said last-named passage.
3. In a radiator, a water chamber, a heat chamber within the water chamber, means for delivering heated air into the heat chamber, and devices operated by the engine for stirring the water in the radiator.
4. In a radiator, a water chamber, a number of heat chambers within the water chamber, means for delivering heated air into one of the heat chambers, a passage for conducting heated air from the first-named heat chamber to the other one, and devices operated by the engine for stirring the water in the radiator.
5. In a radiator, a water chamber, a number of heat chambers within the water chamber, means for delivering heated air into one of the heat chambers, a passage for conduct-

ing heated air from the first-named heat chamber to the other one, a passage for conducting the heated air out of said heat chamber, and devices operated by the engine for stirring the water in the radiator.

6. In a radiator, a water chamber, a number of heat chambers within the water chamber, means for delivering heated air into one of the heat chambers, a passage for conducting heated air from the first-named heat chamber to the other one, a passage for conducting the heated air out of said heat chambers, means for controlling said last-named passage, and devices operated by the engine for stirring the water in the radiator.

7. In a radiator, a crank shaft, means for rotating said crank shaft, and a number of elements operated by said crank shaft for agitating the water in the radiator.

8. A radiator, comprising a radiator shell, tubes forming connections between the upper and lower portions of the radiator shell, a shaft within the upper portion of the radiator shell, and elements in connection with said shaft and extending downwardly therefrom into said tubes for agitating the water in the radiator.

9. A radiator, comprising a radiator shell, tubes connecting the upper and lower portions of the radiator shell, a shaft within the upper portion of the radiator shell, means for rotating said shaft, and elements operated by said shaft for agitating the water within the tubes.

10. A radiator, comprising a radiator shell, tubes connecting the upper and lower portions of the radiator shell and forming communications for the passage of water, a crank shaft within the upper portion of the radiator shell, a crank shaft within the lower portion of the radiator shell, rods connecting said crank shafts and extending through said tubes, and mechanism for rotating one of said shafts to operate the tubes.

CHARLES E. RENO.
